(57) **CLAIM**

The ornamental design for a parking lot platform structure, as shown and described.

DESCRIPTION

FIG. 1 is an elevated front perspective view thereof.

FIG. 2 is a front side direct view thereof.

FIG. 3 is a right side direct view thereof.

FIG. 4 is a left side direct view thereof.

FIG. 5 is a top view thereof; and,

FIG. 6 is an elevated corner side perspective view thereof.

The broken lines in the figures show portions of the building exterior that form no part of the claimed design.
